United States Patent Office

Des. 224,460
Patented July 25, 1972

224,460
BOOTJACK

Earl R. Wright, 200 E. Industrial Blvd.,
Comanche, Tex. 76442

Filed Dec. 1, 1970, Ser. No. 26,237

Term of patent 14 years

Int. Cl. D3—99

U.S. Cl. D86—10

FIG 1

FIG 2

FIG 3

FIG 4

FIG. 1 is a top, side perspective view of a bootjack showing my new design;

FIG. 2 is a side elevation thereof, the side opposite being a mirror image;

FIG. 3 is a bottom plan view thereof; and

FIG. 4 is an end elevation thereof as seen from the right of FIG. 2.

I claim:

The ornamental design for a bootjack, as shown and described.
